MULTIPLE FILING SPINDLE

Axel H. Youngstrom, Minneapolis, Minn.

Application March 3, 1944, Serial No. 524,869

1 Claim. (Cl. 129—21)

1

This invention relates to a multiple filing spindle for temporarily filing checks and other papers.

It is a general object of the invention to provide a multiple filing spindle unit which includes a pair of connected and relatively movable spindle base elements each having a substantially vertical filing spindle extending upwardly therefrom and wherein the base elements and spindles when separated from each other provide a pair of separate filing spindles, but when the bases and spindle elements are moved together they comprise a single base and spindle unit.

Another object of the invention is to provide a conventional base and spindle extending upwardly therefrom and a composite spindle unit movably secured thereto wherein said composite unit can be manipulated to provide a single spindle or a double spindle with two spindle elements spaced from each other.

These and other objects and advantages of the invention will more fully appear from the following description made in connection with the accompanying drawing, wherein like reference characters refer to the same parts throughout the views, and in which:

Fig. 1 is a plan view of an embodiment of the invention with a portion broken away and with an alternate position thereof in dotted lines;

Fig. 2 is a side view of the device with a portion of one of the bases broken away;

Fig. 3 is an enlarged transverse section taken approximately on the line 3—3 of Fig. 1; and

Fig. 4 is an enlarged transverse section taken approximately on the line 4—4 of Fig. 2.

In the drawing, at the right hand portions of Figures 1 and 2 is shown a one-piece spindle base 5 having a perpendicular spindle rod 6 extending vertically therefrom, the lower end of the spindle 6 being threaded into the base 5 as indicated at 7.

Pivottally mounted upon the spindle 6 are laterally extending arms 8 and 9 which are held adjacent the base 5 by means of a nut 10 on the spindle 6. The rod 8, as best shown in Fig. 3, is of channel formation with an open side and the rod 9 is relatively thin and flat and adapted to swing into the channel shaped arm or rod 8. The rod 9 is provided with a dimple 11 adapted to receive a projection 12 struck inwardly on the outer channel shaped rod 8. Thus the two rods are yieldingly held together against relative swinging movement about the spindle 6.

Secured to the left hand end of the rod 8 as by rivets 13 is a substantially semi-circular spin-

10 dle base element 14, and a similar complementary base element 15 is secured to the left hand end of the rod 9. The pivoted rods 8 and 9 and their complementary base portions 14 and 15 are so arranged that when the two rods are swung together as in the full line position of Figure 1 the straight sides of the semi-circular base elements 14 and 15 will contact each other. Midway of the straight sides or edges of the complementary base elements 14 and 15 are complementary spindle elements 16 and 17. The semi-circular cross sectional shape of each of the spindle elements 16 and 17 and their location relative to the complementary base members 14 and 15 permit them to lie closely adjacent each other with their straight sides in contact so that when the arms 8 and 9 and base elements 14 and 15 are swung together the spindle members 16 and 17 provide in effect a single spindle unit.

20 When the device is swung to the full line position of Figure 1 the entire structure provides a spindle 6 and a second spindle made up of the complementary spindle portions 16 and 17. However, if an additional spindle is needed the arms 25 8 and 9 and base elements 14 and 15 can be swung away from each other, the complementary spindle members 16 and 17 thereby being separated from each other so that a three-spindle unit is provided.

30 The device is of relatively simple construction and of compact form. When it is used as a double spindle unit there is no unused third spindle present which might otherwise get in one's way or be a source of possible danger to the person 35 using the spindles since an unused spindle adjacent the others might be forgotten while the attention of the user is directed to the other two. However, the device can be quickly adjusted to provide three spindles when that number of the 40 device is required and actually being used.

It will, of course, be understood that various 45 changes may be made in the form, details, arrangement and proportions of the various parts without departing from the scope of my invention.

What I claim is:

In a filing spindle, a first base element having a spindle extending upwardly therefrom, a pair of complementary base elements each having a spindle extending upwardly therefrom, and laterally interfitting bars pivottally connecting said first base element respectively with said complementary base elements.
